CURL HEATER

Melvin D. Fountain, Seattle, Wash., assignor of
fifty-one per cent to E. Mary Brown, Seattle,
Wash.

Application August 26, 1940, Serial No. 354,241

8 Claims. (Cl. 213--24)

My present invention relates to a curler heater for drying the hair after it has been wound on hair curlers.

It is well known in the beauty trade that the drying of the curled hair to which has been applied a curling solution is always a tedious and slow process. The hair, when it is curled, is usually treated with a curl setting solution that is of a heavy consistency and will only dry slowly. The hair is wound on a curler element of metal and then clamped in place. If allowed to dry normally it will take a considerable length of time. Any means adapted for speeding up this operation would undoubtedly make the curling of the human hair greatly more desirable and convenient.

Auxiliary equipment for the drying of hair curls must, of necessity, be of simple construction, readily adaptable to the hair being curled. It must be operable on a low voltage so that there will be eliminated as much as possible of the chance for electrical shock or other injury.

The preferable form of such a device would also include the application of heat at a relatively low temperature, but at the same time high enough to speed up the drying of the hair. Its application should be to the center of a curl so that all of the curl can be simultaneously treated while at the same time heat radiated over the exterior of the curl can assist in carrying away the moisture therein.

It is an important object of my invention to provide a curl heater or curl dryer which may be electrically operated and which may be groped in a series that will be applied to a series of curls with great rapidity.

Another object of my invention has been the provision of a curl heater which may be associated with others of like nature in an electrical series arrangement and the whole device operated from a supply source of approximately 110 volts of electricity.

A further object of the invention is related to the provision of a curl heater which is of extremely simple construction, readily adaptable to the present modes of electrical manufacture and including standard electrical equipment to insure their production at a low cost.

Other objects and advantages of the invention will be apparent during the course of the following description, in which I have shown a preferred embodiment of my invention.

In the drawings—

Figure 1 shows in plan view an electrical assembly of a plurality of the heaters of my in-

vention electrically connected in the manner later to be described.

Figure 2 shows the manner in which the heater is applied to a series or group of curls on the head of a person who is awaiting the drying of the curls.

Figure 3 is an enlarged plan view of the heater applied to a curler mechanism of the standard type commonly used in the curling of the human hair.

Figure 4 is a medial section of a curler having applied thereto the heater bar of a curl heater of my invention.

Figure 5 is a cross-sectional view, somewhat enlarged, showing the application of the heater to a curler with a coil of hair indicated as wrapped around the curler.

Figure 6 is a sectional view taken on line 6—6 of Figure 4.

Figure 7 is a perspective view of my curl heater unit.

Figure 8 is an enlarged medial sectional view through the heater element.

Figures 9, 10, 11, and 12 are cross-sectional views taken through the enlarged showing of Figure 8 at the points indicated by lines 9—9, 10—10, 11—11 and 12—12, respectively.

Figure 13 is a perspective view of a U-shaped heater bar or rod as it would appear when removed from the heater unit.

Figure 14 is a perspective view illustrating the manner of attaching the coil wires of the heater element to a supply cord of the usual type.

Figure 15 is a diagrammatic view of the wired electrical circuit showing a plurality of heater units assembled as indicated in Figure 1, and

Figure 16 is a perspective view of a conventional type of curler mechanism.

Referring to the drawings, and especially Figure 1, the numeral 20 designates an extension cord or electrical conductor of the usual insulated or rubber-covered type. A pronged plug 21 is attached to one end of the cord and an intermediate or interline push-through type switch 22 is also provided.

Distributor head 23 receives the ends of a plurality of conductor wires 24, each of which leads to a heater element designated by the numeral 25.

In the diagrammatic showing of the electrical circuit, which may be seen in Figure 15, it will appear that from the two wires of the extension cord 20 is arranged in series the two wires of each of the conductor cords 24. The electrical coils or elements E are attached between the ends of the wires in conduit 24. The elements E are

arranged together in the device in what is referred to commonly as an electrical series arrangement.

Referring now to Figure 8, wherein the general arrangement of parts may be clearly seen, a casting 26 is illustrated as inclosing the electrical coiled element E above referred to. The electrical element E is embedded in insulation material and may be wrapped around or formed adjacent a tubular bushing 28, in which is placed the end 30 of the U-shaped heat conductor bar 32. The bar 32 also has the leg 34 which is used in a manner later to be described.

The two leads of the element E are inserted in the ends of the two compressible connector members 36 and 36' (see Figure 14) and the two ends of the lead-in wire 24 are also inserted in the opposite ends of the elements 36 and 36'. To eliminate the chance of arcing or the short-circuiting between the member and the member 36', I employ an insulation bushing 38 which encircles the member 36' and separates it from the member 36.

To prevent separation of the ends of the two wires forming the conduit 24 I pass the tie member 40 around the conductor wire 24 and secure it tightly in place.

The bar of the U-shaped conductor rod 32 passes through a notch in the end of the body member 26 and a cap 42 fits therein and closes that end of the body. A cross-pin 44 is useful in retaining the cap 42 in position.

In Figures 3, 4, and 16, I have illustrated a conventional type of curler member which is commonly used in curling the hair. This member forms no part of this application, but is merely illustrated for the purposes of explaining the operation of my heater or dryer mechanism. The curler may consist in this case of a perforate tube 46 which has pivoted to one end a segmental member 48, also perforate and a U-shaped wire member 50. Ordinarily a rubber ball 52 snaps over the open end of the tubular member 46 and retains the bar longitudinally along the sides of the tubular member. An end of the hair to be curled is inserted between the tubular member 46 and the member 48. The clamp member 48 is firmly clamped down against the tube by pressure being applied to close the clamp on the tube. The hair is then wound around the portion of the tube 46 which is exposed, as well as around the arcuate or segmental member 48 until a sufficient amount has been wound thereon to form a proper curl. The hair coiled on the tube or curler is indicated by numeral 47.

When the curl is properly wound on the curler, the retainer member 50 is clamped into place and the drying step of the curling process may begin.

In order to facilitate the drying of the hair, I insert the bar 34 of my curler into the opening in the center of the tube 46. For each curl that has been formed on a curler, a heater bar or dryer member will be provided and inserted into the tube. The electrical plug 21 is then inserted into a suitable outlet receptacle, the switch 22 closed to energize the circuit and the elements E within the body 26 will begin to heat. The elements E will be only of such capacity as will heat the bar 34 to a sufficient degree to speed the drying of the hair, but at the same time will not be so hot as to burn the skin upon contact.

The bar 34 when it is heated and within the center of the tube 46 of the curler, will cause heat to radiate throughout the interior of the curl to materially assist in the dispersion of the

moisture which may be in the curl. At the same time the body 26 enclosing the heater element will also heat the exterior portion of the curl adjacent which it lies. By rotary adjustment of the heater device with relation to the curl, the exterior of the curl may be progressively heated throughout its entire circumference. It will be apparent, however, that the heat radiating from the body 26 will probably be considerably lower than the heat radiating from the bar 34, due to the insulation provided in the body 26.

It is my intention to construct the heater unit and the electrical element therein of extremely lightweight material for the purpose of providing a unit which will not overly tax the user by burdening the hair. By properly suspending the distributing head 23 somewhat above the head of the wearer the majority of the weight of the conductor wire 24 can also be relieved from the head.

The foregoing description and the accompanying drawings are believed to clearly disclose a preferred embodiment of my invention, but it will be understood that this disclosure is merely illustrative and that such changes in the invention may be made as are fairly within the scope and spirit of the following claims.

I claim:

1. In a curler heater of the type wherein an electric extension cord having connector means for engagement within an outlet receptacle and also having a switch for opening and closing an electrical circuit is also provided with a distributor head and a plurality of double-wire electrical conductor cords associated with said distributor head and electrically joined together in a series arrangement, a heater on each cord comprising a tubular casing of electrically non-conductive material having means for receiving an end of one of said double-wire electrical cords, said casing also formed with an open end having a lateral notch, a coiled electrical element within said casing in series with the wires of said conductor cord, an electrical bushing in the coil of said element, a U-shaped conductor bar having one leg disposed in said encircled bushing and the other leg disposed outside of said casing parallel to the longitudinal axis thereof, the cross position of said U-shaped bar engaging in the notch in the casing and a plug closing the open end of said casing, and having means for engaging over a portion of the U-shaped bar as it passes through the notch in the casing.

2. In a curler heater of the type wherein an electric extension cord having connector means for engagement within an outlet receptacle and also having a switch for opening and closing an electrical circuit is also provided with a distributor head and a plurality of double-wire electrical conductor cords associated with said distributor head and electrically joined together in a series arrangement, a heater on each conductor cord comprising a heater casing having means for receiving an end of one of said double-wire electrical cords, said casing also formed with an open end having a lateral notch, an electrical element within said casing in series with the wires of said conductor cord, an electrical bushing in the coil of said element, a U-shaped conductor bar having one leg disposed in said encircled bushing and the other leg disposed outside of said casing parallel to the longitudinal axis thereof, the cross portion of said U-shaped bar engaging in the notch in the casing and a plug closing the open end of said casing, and

having means for engaging over a portion of the U-shaped bar as it passes through the notch in the casing.

3. In a curler heater of the type wherein an electric extension cord having connector means for engagement within an outlet receptacle and also having a switch for opening and closing an electrical circuit is also provided with a distributor head and a plurality of double-wire electrical conductor cords associated with said distributor head and electrically joined together in a series arrangement, a heater on each conductor cord comprising a tubular casing of electrically non-conductive material having means for receiving an end of one of said double-wire electrical cords, said casing also formed with an open end having a lateral notch, an electrical element within said casing in series with the wires of said conductor cord, a U-shaped conductor bar having one leg associated with said electrical element and the other leg disposed outside of said casing adjacent thereto, the cross portion of said U-shaped bar engaging in the notch in the casing and a plug closing the open end of said casing and having means for engaging over a portion of the U-shaped bar as it passes through the notch in the casing.

4. In a curler heater of the type wherein an electric extension cord having connector means for engagement within an outlet receptacle and also having a switch for opening and closing an electrical circuit is also provided with a distributor head and a plurality of double-wire electrical conductor cords associated with said distributor head and electrically joined together in a series arrangement, a heater on each conductor cord comprising a casing of electrically non-conductive material having means for receiving an end of one of said double-wire electrical cords, said casing also being formed with an open end, a coiled electrical element within said casing in series with the wires of said conductor cord, a U-shaped conductor bar having one leg passing through said open end and associated with said electrical element and the other leg disposed outside of said casing parallel to the longitudinal axis thereof, and a plug closing the open end of said casing.

5. In a curler heater of the type wherein an electric extension cord having connector means

for engagement within an outlet receptacle and also having a switch for opening and closing an electrical circuit is also provided with a distributor head and a plurality of double-wire electrical conductor cords associated with said distributor head and electrically joined together in a series arrangement, a heater on each conductor cord comprising a casing of electrically non-conductive material having means for receiving

5 an end of one of said double-wire electrical cords, a coiled electrical element within said casing in series with the wires of said conductor cord, and a U-shaped conductor bar having one leg associated with said electrical element and the other leg disposed adjacent the outside of said casing.

6. In a curler heater of the type wherein an electric extension cord having connector means for engagement within an outlet receptacle and also a plurality of double-wire electrical conductor cords associated with said extension cord and electrically joined together in a series arrangement therewith, a heater on each conductor cord comprising a casing of electrically non-conductive material having means for receiving 10 an end of one of said double-wire electrical cords, an electrical element within said casing in series with the wires of said conductor cord, and a U-shaped conductor bar having one leg disposed in said encircled bushing and the other leg disposed adjacent the outside of said casing.

7. A curler heater comprising a U-shaped member, an electrical heater element associated with one leg of said member and adapted to impart heat thereto, and means for conducting 20 electrical energy to said element, the other leg of said U-shaped member forming a radiator portion to engage a hair curler and lying wholly alongside said first mentioned leg and its heater element.

8. A curler heater comprising a U-shaped member, an electrical heater element coiled about one leg of said member and adapted to impart heat thereto, and means for conducting electrical 25 energy to said element, the other leg of said

40 U-shaped member forming a radiator portion to engage a hair curler and lying wholly alongside said first mentioned leg and its coiled heater element.

MELVIN D. POUNTAIN.
